WIRE LINE SETTING TOOL AND WELL PLUG

George Boer, Wallace M. O'Reilly, and Martin E. True, Houston, Tex., assignors, by mesne assignments, to Esso Research and Engineering Company, Elizabeth, N.J., a corporation of Delaware

Application May 17, 1954, Serial No. 430,116

1 Claim. (Cl. 166—181)

This application is directed to a wire line setting tool and well plug.

When performing operations in a borehole, it is often necessary or desirable to have a plug arranged so that it may be lowered at the end of a wire line and set at a predetermined location. The present invention is directed to a wire line setting tool for setting a well plug and to a well plug.

Other objects and advantages of the present invention may be seen from the following description taken with the drawing in which

Fig. 1 is a view, partly in section, showing the upper end of a wire line plug setting tool; and Fig. 1-A is a view, partly in section, showing the lower end of the tool of Fig. 1 with a well plug attached thereto in position for running down a borehole, the two figures being taken together to show a complete tool attached to the well plug;

Fig. 2 is an elevation, partly in section, showing the well plug as set in a section of pipe; and

Fig. 3 is a cross-sectional view along line 3—3 of Fig. 1.

Turning now specifically to the drawing, a section of pipe A represents a casing or tubing in the well in which a plug is to be inserted. Supported on the end of wire line B terminating in a conventional overshot C is the plug setting tool, the principal parts of which consist of a body D divided into chambers E and F with a slideable valve element G in chamber F which has its upper end secured to sleeve H and is slideable with respect to body D and with stem J slideably arranged inside sleeve H, the two parts being pinned together and to body D by pin K. The lower end of the setting assembly is provided with a well plug engaging assembly L which is held in an engaging position with the plug by slideable sleeve M.

The well plug has body or mandrel N which terminates at its upper end in head Q. A passage O extends from an inlet in head Q down through the upper end of body N and discharges through side ports. The central passage is provided with a check valve P. A rubber sleeve R is arranged around mandrel N with its upper end sealed thereto by sleeve S and its lower end sealed thereto by sleeve T.

As will be seen in Fig. 2, when a fluid is introduced into the central passage O of the well plug assembly, when the pressure is sufficient to overcome the exterior pressure on sleeve R, the sleeve expands outwardly and makes a fluid-tight seal with the section of pipe A. The fluid pressure is retained within the plug by check valve assembly P. A means for releasing the plug is shown and claimed in copending patent application No. 430,117 entitled "Wire Line Releasing Tool and Well Plug," filed May 17, 1954, in the names of George Boer, Wallace M. O'Reilly and Martin E. True.

Taking up specifically the plug setting tool as shown in Figs. 1 and 1-A, the upper end of body D terminates in sleeve 11 in which member J is slideably arranged and around which tubular member H is slideably arranged. Pin K serves the dual purpose of holding tubular mem-

2

ber H against movement with regard to body D and with regard to the member J. Pin K may be sheared at points 12, 12 by dropping a sleeve (such as sleeve 13) down wire line B so that it strikes bumper 14 mounted on the upper end of sleeve H. Pin K may also be sheared at points 15, 15 if the body D is held against upward movement and a sufficient pull is exerted on wire line B.

Member J is provided with a head 16 for engagement with wire line member C and its lower end is provided 10 with an outwardly extending circular ledge 17 which fits within the lower end of sleeve member H with its movement in sleeve member H limited in the upward direction by circular shoulder 18 and its movement in the downward direction limited by circular member 19.

Member 20 of valve assembly G is secured to sleeve H by means of a circular head 21, the upper surface of which abuts the lower surface of member 19 and the lower surface of which abuts circular member 22, members 19 and 22 being secured to the sleeve by conventional screw threads. Member 20 of valve assembly G has secured thereto lifting arm 23, the ends of which fit into slots 24 of outer sleeve M.

The upper end of body D has a partition 25 in which is a central passage 26 in which valve member 20 fits 25 slidingly with the upper end of the partition sealed by seal 27 and the lower end sealed by seal 28. A passage 29 connects the space of cylinder E with the exterior of body D and is controlled by check valve 30 which allows the entrance of fluid into chamber E but prevents its release.

Body D has a central partition 35 provided with a central passage 36 in which is arranged seal 37 and through which the lower end of valve member G fits slidingly. Partition 35 is provided with longitudinally extending passages 38, 38 which connect the lower end of chamber E with the upper end of chamber F and are controlled by check valves 39, 39 which allow excess pressure to pass from chamber F to chamber E but prevent the flow of fluid from chamber E to chamber F.

Body D has at its lower end a circular shoulder or wall 40 terminating in a wedge-shaped end 41 which slopes upwardly and outwardly. Above circular wall 40 is partition 42 through which extends a central passage 43 which communicates chamber F with the exterior of body D, the end of the central passage 43 being surrounded by sealing member 45 which is adapted to make a fluid-tight seal with the upper end of body N of the well plug as shown in Fig. 1-A so that when the well plug is secured to the setting tool passage 43 of the tool and passage O of the well plug form a continuous conduit for the flow of fluid.

The means L which secures the well plug to the setting tool assembly consists of a plurality of arms 50, 50 each of which is secured at its upper end to body D by screw 51 and has its lower end terminating in a dog 52 which fits into neck 53 of the body N of the well plug. Each dog 52 has an upper shoulder 54, the surface of which is parallel with annular surface 41 of body D but the dog extends farther inwardly than does the shoulder 41 so as to engage with the head Q of the well plug. The dog 52 is held against outward radial movement by sleeve M. However, when sleeve M is moved upwardly along valve body D, the arms 50 are exposed, and this allows the dogs 52 to move outwardly so that the dogs can ride over shoulders 55 of head Q thereby releasing the well plug 65 assembly from the setting tool assembly.

The central partition 35 of body D has secured thereto upwardly extending tubular member 60 in which valve member G is slideably arranged with the upper end of the tubular member provided with a seal 61 sealing it to member G. Member G is provided with a lower central passage 62 which communicates to the exterior through

side port 63 at its lower end and communicates to the exterior through side port 64 at its upper end. Valve member G also has an upper central passage 65 which communicates to the exterior of the member G at its lower end through side port 66 and communicates with the exterior at its upper end through valve port 67.

Slidesly arranged within chamber F is a piston 68 which in effect divides the chamber into two parts, a lower chamber 69 and an upper chamber 70.

To use the device for lowering a well plug and setting it in a string of pipe, the setting tool and packer are assembled as shown in Figs. 1 and 1-A. The space 69 of chamber F, passage 43 of the setting tool and passage O of the well plug are filled with a suitable hydraulic fluid. Chamber E is filled with a suitable high pressure gas which is sealed in chamber E by valve G with valve G in turn held in position by sleeve H pinned to the body D and to the member J by pin K. The well plug is secured to the lower end of the well setting tool by assembly L, the dogs in turn being held in position in neck 53 of the packer body N by sleeve M.

The assembly is lowered through the string of pipe until the well plug is at the desired setting point. Sleeve 13 is then dropped down wire line B and upon striking bumper shoulder 14 of sleeve H shears pin K at points 12 and causes sleeve H with attached valve member G to move valve member G to its lowermost position where side port 63 is below partition 35 but side port 64 is above seal 61; this allows high pressure gas to discharge from chamber E into the upper portion 70 of chamber F which in turn forces piston 68 downwardly and drives hydraulic fluid from portion 69 of chamber F through central passage 43 of body D and central passage O of well plug body N to expand the rubber sleeve outwardly as shown in Fig. 2.

After the packer has been set, the release of the running tool from the packer body is initiated by pulling upwardly on wire line B which causes shear pin K to shear at points 15. Since sleeve member H previously had moved downwardly when pin K sheared at points 12, shoulder 17 of member J is in contact with shoulder 18 of member H. Continued upward movement of the wire line thus causes member J, sleeve member H, valve member G and cross pin 23 to move upwardly together. The movement upwardly of valve member G causes it to move from its lower third position to its upper first position. When valve member G is in its upper position side port 66 communicates passage 65 through side port 67 with the exterior of the body and releases excess pressure from chamber E to the exterior of the body. The bleeding off of pressure from chamber E in turn allows gas from portion 70 of chamber F to pass through check valves 39 and passages 38 into chamber E and in turn bleed to the exterior, the result being that the excess pressure is released from both chambers E and F. Movement upwardly of cross pin 23 causes it to engage with the upper end of slots 24 of sleeve M and additional movement draws sleeve M upwardly to expose dogs 52 and arms 50. Continued movement upwardly of cross pin 23 causes it to engage with the upper end of slots 90 of the upper portion of the body D to withdraw the well setting tool from the plug assembly when dogs 52 are released so that the well setting tool assembly may be withdrawn to the surface of the earth.

While a specific embodiment of the present invention has been disclosed, it will be obvious that various changes in the sizes, shapes and proportions of the several parts may be made without departing from the scope of the invention.

The invention claimed is:

A wireline setting tool adaptable for use with a fluid

expandable well plug, said well plug including an inflatable sleeve, a fluid inlet passageway communicating the interior and exterior of said sleeve, and a check valve in said passageway adapted to normally prevent escape of fluid from said sleeve, said tool comprising an elongated body having upper and lower chambers, said upper chamber being adapted to contain a high pressure fluid medium, said lower chamber being provided with a downwardly facing fluid outlet port and a low pressure fluid medium therein, a piston in said lower chamber spaced vertically above said outlet port, a partition member in said body forming and separating said chambers, releasable arms secured to, and extending below, the lower end of said body adapted to engagedly connect with said well plug, said lower chamber outlet port and said inlet passageway being aligned and in fluid communication when said arms engagedly connect with said well plug, sealing means carried by the lower end of said body for sealingly engaging said plug adjacent said aligned outlet port and said inlet passageway, a cylindrical member slidably mounted on said body and normally positioned to telescope over said releasable engaging arms to retain said arms engagedly connected to said well plug, valve means mounted in slidable relation to said partition and chambers adapted to have first, second and third positions, said valve when in said first position fluidly communicating the upper chamber with the exterior of said body, said valve when in said second position fluidly communicating said upper chamber and said lower chamber and said valve when in said third position preventing fluid flow between said upper and lower chambers and between said upper chamber and the exterior of said body, a stem member mounted in said body exteriorly of said chambers and adjacent said valve means and movable relative to said valve means, abutment means on said stem member and valve means, a shear pin normally connecting said stem member, said body and said valve means together with said abutment means spaced from each other and positioned so that said valve means is arranged in said third position, the portion of the shear pin connection between said body and said valve means being adapted to be broken by an external force applied thereto to release said valve means from said body and to permit said abutment means to become engaged, and said valve means to move from said third to said second position whereby said high pressure fluid medium will move said piston to force the fluid in the lower chamber through said inlet passageway into the interior of said inflatable sleeve, wireline means adapted to be connected to said stem member and the body connected thereto by the remaining portion of said shear pin when said valve means is in said second position, lost motion linkage means interconnecting said valve means and said cylindrical member, said remaining shear pin connection portion being adapted to be fractured by a force applied to said wireline whereby said wireline may move said stem member and said valve means by means of said abutment means to cause said valve means to assume said first position and whereby said cylindrical means is simultaneously moved to disengage from said retaining arms.
